UNITED STATES PATENT OFFICE

FREDERICK L. G. STRAUBEL, OF GREEN BAY, WISCONSIN, ASSIGNOR TO THE AUTOMATIC FILE & INDEX CO., OF GREEN BAY, WISCONSIN, A CORPORATION OF WISCONSIN

TOP-OPENING FILING CABINET

Application filed April 14, 1930. Serial No. 444,119.

My invention relates to top-opening filing cabinets, and in its general objects aims to provide a cabinet in which the opening of the cover simultaneously moves the cover to a 5 position permitting free downward access to the contents of the cabinet, and tilts the front of the cover of the cabinet forwardly to expand the effective upward opening of the cabinet.

10 In the class of cabinets used for filing letters, it has heretofore been customary to support both the letters, the interposed guides and the usual adjustable follower on a slide which is fastened to a frontal cabinet portion 15 and is adapted to be drawn partly out of the cabinet to permit access to the letters. It has also been found advantageous to hinge a movable cabinet front portion at its bottom to the corresponding slide, so that this frontal 20 portion can be tilted to permit a separation of the upper portions of the letters, thereby greatly facilitating access to each such section of the cabinet.

Where a cabinet is of a single deck height, 25 as distinguished from a so-called three-drawer or four-drawer height, this is not feasible, since the weight of the extended slide in a full or even in a partly filled drawer will overbalance the weight of the casing of the cabinet, so as to tilt or even upset the entire cabinet. Moreover, the needed slide arrangement, including the rollers and extension slide portions usually required to reduce friction, add undesirably to the cost of a single tier cabinet such as 30 is desirable for many purposes. Consequently, any provision for permitting an access-facilitating expansion of the contents of a single tier cabinet has not been feasible, thereby interfering greatly with the effective use 40 of such single tier cabinets.

My present invention aims to overcome these objections by providing a single-tier cabinet requiring no slide or other movable support for the file contents, aims to provide novel means for supporting the movable cover of the cabinet and for swinging this cover effectively out of the way when raised, and 45 aims to provide simple means whereby the

raising of the cover also tilts the front of the cabinet forwardly.

Moreover, my invention aims to provide means connecting the movable cover with the movable front whereby a return of the cover to its normal position will simultaneously 55 return the front to its normal position, and for this purpose aims to provide connecting means so arranged that rearward pressure on the cabinet front when in its forwardly 60 tilted position will not effect a closing of the cover.

Furthermore, my invention aims to provide a simple, compact and inexpensive cabinet construction for these purposes and one 65 which can readily be employed in an all-metal (and hence fireproof) cabinet.

Still further and also more detailed objects will appear from the following specification and from the accompanying drawings, 70 in which

Fig. 1 is a central, vertical and longitudinal section through a closed filing cabinet embodying my invention.

Fig. 2 is a similar section, showing the 75 cabinet in its opened position.

Fig. 3 is a fragmentary transverse section, taken along the line 3—3 of Fig. 1 but drawn on a larger scale.

Fig. 4 is a perspective view of the cabinet, 80 drawn on a reduced scale.

In the illustrated embodiment, the main and stationary portion of my cabinet includes a bottom 1 rigidly secured (as by welding) to a back 2 and sides 3. The front of this 85 stationary cabinet portion is normally closed by a front 4 which is connected at its lower end by hinges 5 to the bottom 1, so that this front can be tilted forward about a horizontal axis extending transverse of the cabinet. 90

Extending rearwardly from the front 4 at its opposite side edges are wings 6, each of which wings is pivotally connected at a considerable distance above the axis of the hinges 5 to the forward end of a link 7 which has its rear end pivotally connected to the free end of an arm 8 of a bell-crank lever. This lever is pivoted adjacent to the juncture of its arms to the adjacent side 3 of the cabinet by a pivot pin 9; and when the cabinet is closed, the 95

said lever arm 8 depends downwardly from the said pivot pin (as shown in Fig. 1) while the companion arm 10 of the bell-crank lever extends forwardly and slopes upwardly beyond the upper edge of the adjacent side 3 of the main portion of the cabinet. This companion lever arm 10, which desirably is longer than the first named arm 8, is pivoted at its free end to the adjacent side portion 12 of the hereafter described cover.

Normally closing the mouth of the stationary cabinet portion is a cover comprising as a rigid assembly a cover top 11, cover side portions 12, a frontal cover end 13 and a rear cover end 14, all four of which cover portions may have their lower edges seated on the upper edges of the main portion of the cabinet and of the movable front 4.

Instead of being hinged to the main portion of the cabinet after the heretofore customary manner, this cover is connected to the main and upwardly opening cabinet portion only by the aforesaid two lever arms 10 and by two rear links 15, which links are respectively adjacent to the opposite sides 3 of the cabinet. Each rear link 15 is considerably shorter than one of the counterpart lever arms 10 and extends rearwardly downward within the closed cabinet, the lower end of each rear link being pivoted to the adjacent cabinet body side 3 rearwardly of the pivot pin 9 of the adjacent bell-crank lever.

When the front of the cover is lifted, as by raising a knob 16 fastened to the frontal cover end 13, the lever arms 10 and the links 15 cooperate to raise the forward portion of the cover to a greater extent than its rearward portion, and to swing the upper ends of both the said lever arms and links rearwardly beyond the pivotal connections of these connecting parts to the cabinet body, until the swinging movement of the cover is halted by the engagement of the rear links 15 with the upper edge of the back 2 of the body of the cabinet. The links 15 and the longer lever arms 10 then cooperate (as shown in Fig. 2) in supporting the cover in an approximately upright position in which the cover partly depends behind the cabinet body and permits free downward access to the interior of the cabinet.

To move the front 4 forwardly while the cover is being swung from the closure position of Fig. 1 to the opened position of Fig. 2, I connect the free end of each depending lever arm 8 by a link 7 to the movable cabinet front, desirably by providing this front with rearwardly extending wings 6 respectively adjacent to the sides of the cabinet, to which wings the forward ends of the links 7 are respectively pivoted.

During the swinging of the cover from its closed to its said open position, the rocking of the bell-crank levers about their pivots 9 also swings the depending lever arms 8 so as

to move the forward ends of these lever arms 8 forwardly, thereby pushing the links 7 forwardly and causing these links to rock the cabinet front 4 forwardly about the hinges 5. Consequently, the opened cabinet is effectively enlarged in length adjacent to the mouth of the cabinet; thereby permitting the contents of the cabinet to be spread apart at the top to facilitate the insertion and removal of papers, and to permit an inspection of papers without even taking them out of the file.

When the cabinet is to be closed, a forward pull on the knob 16 simultaneously rocks the upper lever arms 10 and the rear links 15 about their pivotal connections to the sides of the cabinet body, so that these lever arms and short links cooperate to swing the cover back until it rests on the upper edge of the cabinet as shown in Fig. 1. Since the just mentioned pivotal connections are at considerable distances from the front of the cabinet, any looseness in these connections might prevent the cover from alining laterally with the cabinet body (or stationary portion of the cabinet) when the cover is closed. Hence I desirably provide means adjacent to the front of the cabinet for insuring this alinement, so as to exclude dust; as for example by providing each cover side with a clip finger 17 adapted to depend along the inner face of the corresponding body side 3 (as shown in Fig. 1) when my cabinet is closed.

I also desirably provide a guard plate 48 adjacent to each side portion 3, which guard plate has its major portion offset inwardly from the adjacent cabinet side, (as shown in Fig. 3) to provide a space within which the adjacent link 7, and the lower portions of both the adjacent lever and rear link can operate, each guard plate having an aperture 48A in an offsetting portion through which a lever arm 10 and a link 15 freely extend. Each guard plate then prevents the adjacent lever and links from engaging and damaging the contents of the cabinet.

In practice, the relative lengths of the lever arms and of the links, as well as the locations of the various pivotal connections may be varied considerably. However, I preferably arrange these so that during the opening of the cabinet each pivot pin 19 (which connects one of the front-moving links 7 to the depending arm 8 of the associated bell-crank lever) moves upwardly past the common axial plane of the pivot pins 9 and 18. Then when the cabinet is in its open position of Fig. 2, a rearward pressure on the hinged front 4 will tend to swing the cover still further rearward, so that this cover will not be slammed down to its closure position if the user of the cabinet accidentally presses against the hinged front.

By disposing the pivotal connection of the lower end of each rear link to a cabinet side

5 rearward of the pivoting of a lever to the same side, I permit the lever and rear link at each side of the cabinet to swing without interfering with each other; and by making the forward lever arm longer than the rear link, I effect the action which swings the cover partly behind the back of the stationary cabinet and to an approximately upright position upon a lifting of the frontal portion 10 of the cover.

10 So also, by making the arm 8 (which actuates the movement of the front) integral with one of the members which connects the cover to the stationary cabinet portion, I secure an 15 exceedingly simple and compact mechanism for conjointly moving the cover and the front when the cover is manually moved.

20 However, changes might obviously be made without departing either from the spirit of my invention or from the appended claims, hence I do not wish to be limited to the 25 details of the construction and arrangement above disclosed.

In the claims, it is to be understood that 25 the term "overhangs" is used in the sense of overlying or extending horizontally above.

I claim as my invention:

30 1. In a filing cabinet, a stationary member including two sides and a back; a front pivotally connected at its lower end to the said stationary member; a cover normally seated upon upper portions of the stationary member in a position in which it overhangs the space between the said front, sides and back; means operatively connecting the cover with the stationary portion to permit the cover to be swung upwardly and rearwardly with respect to the said stationary portion, and means associated with the aforesaid means for rocking the front forwardly about its pivotal connection to the stationary member when the cover is swung in the said direction.

40 2. In a filing cabinet, a stationary member including two sides and a back; a front pivotally connected at its lower end to the said stationary member; a cover normally seated upon upper portions of the stationary member in a position in which it overhangs the space between the said front, sides and back; two means spaced longitudinally of the cabinet and connecting the cover with the stationary member, whereby a lifting of the forward part of the cover will swing the cover upwardly and rearwardly; and front-actuating 45 means interposed between the front and one of the aforesaid means, whereby the swinging of the cover in the said direction rocks the front forwardly about its pivotal connection to the stationary member of the cabinet.

50 3. In a filing cabinet, a stationary member including two sides and a back; a front pivotally connected at its lower end to the said stationary member; a cover normally seated upon upper portions of the stationary mem-

ber in a position in which it overhangs the space between the said front, sides and back; two bell-crank levers respectively adjacent to and pivoted to the two sides; each bell-crank lever comprising an upper arm normally sloping upwardly forward from the pivot axis of the lever and connected at its free end to the cover, and a lower arm normally depending from the said pivot axis; and means interposed between the free end 70 of the short arm of each lever and the said front whereby movement of the levers rocks the front about its pivotal connection to the stationary member.

75 4. In a filing cabinet, a stationary member including two sides and a back; a front pivotally connected at its lower end to the said stationary member; a cover normally seated upon upper portions of the stationary member in a position in which it overhangs the space between the said front, sides and back; two bell-crank levers respectively adjacent to and pivoted to the two sides; each bell-crank lever comprising an upper arm normally sloping upwardly forward from the pivot 80 axis of the lever and connected at its free end to the cover, and a lower arm normally depending from the said pivot axis; and two 85 links respectively adjacent to the said two sides, each link being pivoted at its rear end to the lower arm of one of the levers and being pivoted at its forward end to the said front at a considerable elevation above the pivotal connection of the front to the stationary member of the cabinet.

90 5. In a filing cabinet, a stationary member including two sides and a back; a front pivotally connected at its lower end to the said stationary member; a cover normally seated upon upper portions of the stationary member in a position in which it overhangs the space between the said front, sides and back; two bell-crank levers respectively adjacent to and pivoted to the two sides; each bell-crank lever comprising an upper arm normally sloping upwardly forward from the pivot 95 axis of the lever and connected at its free end to the cover, and a lower arm normally depending from the said pivot axis; and two links respectively adjacent to the said two sides and each pivoted at its rear end to the lower arm of one of the levers; the front including two wings extending rearwardly respectively adjacent to the said two sides, each of the said links having its forward end pivoted to one of the wings at a considerable 100 distance above the pivoted connection of the front to the stationary member of the cabinet.

105 6. In a filing cabinet, a stationary member including upright sides and a back; a normally upright front hinged at its lower end to the stationary member on a horizontal axis; a cover normally seated upon upper portions of the stationary member in a position in which it overhangs the space between 110

the said front, back and sides; two rear links respectively connecting the cover to rearward portions of the two sides; two bell-crank levers respectively pivoted to the two sides, 5 each bell-crank lever comprising an arm pivoted at its free end to the cover forwardly of the connections of the aforesaid links to the cover, and including a second arm normally extending downward from the axis 10 on which the lever is pivoted to a side; and two front-actuating links respectively connecting the second arms of the two levers to portions of the front.

7. A filing cabinet as per claim 6, in which 15 the front includes a front plate and two wings extending rearwardly from the front plate and respectively adjacent to the sides of the stationary cabinet portion, to which wings the two front-actuating links are respectively connected.

8. A filing cabinet as per claim 6, in which the first named two links are disposed for engaging the upper end of the back when the cover is swung out of its normal position, 25 thereby limiting the extent of the said swinging.

9. A filing cabinet as per claim 6, in which the two rear links are pivoted to the sides near the upper edges of the said sides and at 30 a less distance from the back than the length of these links, whereby these links are adapted to extend over and rest upon the upper edge of the back to limit the swing movement of the cover out of its normal position.

35 10. A filing cabinet as per claim 6, in which the pivot axes of the levers are lower than the pivot axes of the rear links.

11. A filing cabinet as per claim 6, in which the two rear links are pivoted to the sides 40 near the upper edges of the said sides and at a less distance from the back than the length of these links, whereby these links are adapted to extend over and rest upon the upper edge of the back to limit the swing movement 45 of the cover out of its normal position, the first named arm of each lever being of such a length as to dispose the cover in an approximately upright position when these links thus rest upon the upper edges of the 50 back.

12. A filing cabinet as per claim 6, in which the pivot axis of each lever is so disposed with respect to the angle between its lever arms and the connection of the front 55 to the front-actuating link associated with this lever, that the connection between the front-actuating link and lever is above a line connecting the pivot axis of the lever with the connection of the same link to the cabinet 60 front when this front is swung forwardly to its extreme extent from its normal position; whereby a rearward pressure on the said front will tend to move the levers and links to effect a further movement of the 65 cover away from its normal position.

13. In a filing cabinet, a stationary member including two sides and a back; a front hingedly connected at its lower end to the stationary member; a cover normally seated upon upper portions of the stationary member in a position in which it overhangs the space between the said front, back and sides; and means operatively interposed between the sides, the cover and the front whereby a lifting of the front portion of the cover simultaneously swings the cover rearwardly and tilts it rearwardly downward, and swings the front forwardly about its hinged connection to the stationary member; the said means comprising a lever and link system including two rear links disposed for engaging the back to limit the extent of the said swinging and tilting of the cover, two front-actuating links disposed for swinging the front forwardly, and two levers cooperating with the front-actuating links to prevent rearward pressure on the forwardly swung front from moving the said levers, links and cover.

14. A filing cabinet as per claim 1, in which the cover member has sides normally seated on the upper edges of the sides of the stationary member, in combination with projections on the sides of one member for engaging sides of the other member to prevent lateral movement of the cover with respect to the sides when the cover has its said sides thus seated.

Signed at Chicago, Illinois, April 11th, 1930.

FREDERICK L. G. STRAUBEL.
